UNITED STATES PATENT OFFICE.

HENRY S. DILLS, OF GARRETT, INDIANA.

DESIGN FOR A FISH-BAIT.

58,184.

Specification for Design. Patented June 21, 1921.

Application filed December 11, 1920. Serial No. 430,064. Term of patent 14 years.

To all whom it may concern:

Be it known that I, HENRY S. DILLS, a citizen of the United States, residing at Garrett, in the county of Dekalb and State of Indiana, have invented a new, original, and ornamental Design for Fish-Baits, of which the following is a specification, reference being had to the accompanying drawings, forming part thereof.

The figure is a side elevational view of a fish-bait showing my new design.

I claim:

The ornamental design for a fish-bait as shown.

In witness whereof I have hereunto subscribed my name this 4th day of December, 1920.

HENRY S. DILLS.
